US00D774056S

(12) **United States Design Patent** (10) Patent No.: **US D774,056 S**
 Stein et al. (45) Date of Patent: **** Dec. 13, 2016**

(54) **DISPLAY SCREEN WITH GRAPHICAL USER INTERFACE**

(71) Applicants: **Robert Stein**, New York, NY (US);
Tony Ke, New York, NY (US);
Rasmus Zwickson, Brooklyn, NY (US)

(72) Inventors: **Robert Stein**, New York, NY (US);
Tony Ke, New York, NY (US);
Rasmus Zwickson, Brooklyn, NY (US)

(73) Assignee: **Yahoo! Inc.**, Sunnyvale, CA (US)

(**) Term: **15 Years**

(21) Appl. No.: **29/542,172**

(22) Filed: **Oct. 12, 2015**

(51) LOC (10) Cl. **14-04**

(52) U.S. Cl.

USPC **D14/485**

Assistant Examiner — Nicole Shiflet

(74) Attorney, Agent, or Firm — James J. DeCarlo;
 Greenberg Traurig LLP

(57) **CLAIM**

The ornamental design for a display screen with graphical user interface, as shown and described.

DESCRIPTION

FIG. 1 is a front view of a display screen with graphical user interface;

FIG. 2 is an alternate embodiment of a front view of a display screen with graphical user interface; and,

FIG. 3 is a front view of a display screen with graphical user interface as shown in FIG. 1 with varying broken line elements.

The broken lines showing a display screen and portions of the graphical user interface form no part of the claimed design.

1 Claim, 3 Drawing Sheets
